BUILDING BLOCK

John Keogh, 411 W. Garfield Ave., Glendale, Calif.

Filed Mar. 8, 1960, Ser. No. 59,677

Term of patent 14 years

(Cl. D18—2)

Fig. 1

Fig. 2

Fig. 1 is a perspective view of a building block showing my new design; and

Fig. 2 is a top plan view of the block, the bottom having the same configuration.

I claim:

The ornamental design for a building block, as shown and described.
